UNITED STATES PATENT OFFICE

138,011

DESIGN FOR A COOKING UTENSIL

Dave Chapman, Chicago, and James Harvey Chandler, Oak Park, Ill., assignors to The Edward Katzinger Company, Chicago, Ill., a corporation of Illinois

Application November 22, 1943, Serial No. 111,764

Term of patent 14 years

(Cl. D44—1)

To all whom it may concern:

Be it known that we, Dave Chapman and James Harvey Chandler, citizens of the United States and residing at Chicago and Oak Park, respectively, in the county of Cook and State of Illinois, have invented a new, original, and ornamental Design for a Cooking Utensil, of which the following is a specification, reference being had to the accompanying drawing, forming part thereof.

Fig. 1 is a top plan view of a cooking utensil, showing our new design.

Fig. 2 is a side elevational view of the same. Fig. 3 is a side elevational view thereof, when turned through an angle of 90 degrees relative to the position shown in Fig. 2.

The dominant feature of the design resides in the portion shown in full lines.

We claim:

The ornamental design for a cooking utensil, as shown and described.
